CURRENT-TAPPING CAP-PLUG FITTING AND
THE LIKE ATTACHMENT DEVICESJohn Petry, Flushing, N. Y., assignor to Raylite
Trading Co., Inc., a corporation of New York

Application November 5, 1940, Serial No. 364,392

8 Claims. (Cl. 173—334)

This invention relates to electric attachment fittings, such as cap-plugs, and as here shown are incorporated in an improved construction of a combination current-tapping, cap-plug fitting for detachably connecting one or a plurality of portable electric appliances, lighting systems and the like to an electric power supply outlet receptacle.

Among the objects of the invention is to generally improve electric attachment fittings of the character described, whereby such fittings shall comprise few and simple parts assembled to form a neat appearing, compact, rugged structure, which shall be cheap to manufacture, and which shall be practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claims.

In the accompanying drawings, in which is shown various possible illustrative embodiments of this invention:

Fig. 1 is a side elevational view of a combination current-tapping cap-plug fitting connected with a cap-plug shown in section to expose the interior construction embodying the invention;

Figs. 2 and 3 are an end and front elevational view of the combination current-tapping cap-plug fitting shown in Fig. 1, part of the body portion of the fitting in Fig. 3 being broken away to show the expansion anchorage of the current carrying contact terminal blades or prongs;

Figs. 4 and 5 are cross-sectional views taken on lines 4—4 and 5—5 in Fig. 1, respectively;

Figs. 6 and 7 are perspective views of the current carrying contact terminal blades or prongs, and the current carrying spring contact, respectively;

Fig. 8 is an end view of the improved fitting similar to Fig. 2 showing a modified construction of the invention using screw binding posts instead of soldered connections for the conductor wires;

Fig. 9 is a perspective view of a terminal blade or prong with the screw binding post differing from that shown in Fig. 8; and

Fig. 10 is a cross-sectional view taken on lines 10—10 in Fig. 1 showing details of the invention incorporated in the cap-plug fitting.

Referring in detail to the drawings, 20 denotes

an improved combination current-tapping, cap-plug fitting constructed to embody the invention adapted to connect with conventional base boards and fixture socket or flush outlet receptacles in the well understood manner, such improved fittings 20 having their current-tapping portions adapted to connect with other fittings 30, or with contact terminal blades or prongs 22 of a cap-plug 30 constructed to incorporate certain features of the invention hereinafter described and shown in Figs. 1 and 10, or similarly connected with contact terminal blades or prongs of any standard cap-plug fitting (not shown) in the well known conventional manner.

Any such conventional cap-plug or cap-plug 30 shown in Figs. 1 and 3 may terminate the ends of conductor wire 34 for connecting an electric appliance (not shown) to a suitable power source through the improved current-tapping cap-plug fitting 20 in the well understood manner.

The fitting 20 preferably comprises a one-piece body portion 21 of any suitable shape and formed of insulating material, such as a so-called "plastic," as for example a phenol-condensate material or the like moldable substances which form rigid structures. As here shown, the body portion is cylindrical and has current-carrying members mounted and secured in the manner hereinafter described at spaced diametrically opposite portions of the wall of said body portion 21 inwardly from the peripheral rim 21a thereof as shown in Figs. 1 and 3.

The current carrying members may comprise terminal blade portions 22 extending outwardly from the rear end open side 20a of the fitting body portion 21 and spring contacts 23 which electrically connect with end bases 22a of the blades 22 when assembled in the body portion 21. Said spring contacts 23 extend into a pair of spaced parallelly aligned passages 21b provided in the body portion 21 and communicating with the rear end open side 20a of the fitting 20. Said passages 21b project in from openings 21c provided in the front end closed side 20b of the fitting 20 opposite said rear end open side 20a, said passage openings 21c being shaped and sized to permit the free insertion of blades or prongs 22 of cap-plug 30 or other similar or conventional plugging-in device. The passages 21b may be made the same width as the openings 21c but are slightly larger in breadth to accommodate the breadth of the spring contact 23, said passages 21b being somewhat longer than the length of the plugging-in portion of the blades or prongs 32 so that on insertion of the latter in fittings

20, a small clearance is provided as is clearly shown in Fig. 1.

Adjoining each passage 21b and extending in from the open rear side 20a only partially the length thereof, there is provided a socket or cavity 21d. Each socket or cavity 21d may if desired be separated from the adjoining passage 21b by oppositely extending ledges 21e formed in the common wall therebetween as part of the body portion 21, and the bottom or dead end of each cavity 21d may be provided with a suitable cam means such as a protuberance or wedge 21f integrally molded as part of the body portion 21. See Figs. 3, 4 and 5. The side walls 21g of said sockets 21d extend parallelly in from the open rear side 20a, the width of said socket preferably being enlarged at the inner ends of the side walls 21g, that is, cut back for a length substantially equal to the wedge 21f to provide shoulders 21h and anchoring pockets for expanded split end bases 22a of blade portions 22 as shown in Fig. 3 and in the manner hereinafter described.

As shown in Figs. 1 and 6 the blade portions 22 may be constructed of a metal stamping having the usual circuit connecting prong end 22b and provided with an offset 22c midway the prong end 22b and end base 22a. The latter is split centrally up to the offset 22c to provide spaced tongues 22d and the outer surfaces of said tongues may be cut as at 22e to provide spurs 22f which are adapted to be expanded into anchoring pockets under the shoulders 21h as shown in Figs. 2 and 3.

The spring contacts 23 may preferably be made of a copper sheet metal strip bent to have a right triangular shape and formed with one corner portion detached at 23a as shown in Fig. 7. Such construction permits the adjoining and opposite sides 23b and 23c, respectively, thereof, to be flexed with respect to the other side 23d when operative as shown in Fig. 1. The side 23d may be provided with a lip or flange 23e, the exterior side of said lip 23e being adapted in the assembled fitting 20 to abut and contact the tongues 22d of the blade end base 22a.

The lips or flanges 23e initially are bowed across the width thereof as shown in Fig. 7 which on being assembled gives an extra spring construction to provide an efficient electrical contact, two bosses 23g may be provided for producing a scraping action on being assembled, as is clear from Fig. 1. The lip or flange 23e with the adjacent adjoining side 23c provides another function, namely, the clamping between them the ledges 21e during the process of assembly to avoid accidental displacement of said spring contacts 23 from the passages 21b and prior to inserting the blade base 22a in sockets 21d for mounting and securing the blades 22 in anchored position.

To provide an unbroken peripheral rim 21a about the open side 20a of the fitting 20 yet allow conductor wires 24 to extend through the side wall of the body portion 21, an opening 21j is provided. To this end, the rim 21a is made larger in diameter than the portion of the body portion extending down from the closed side 20b above said rim and thus forms a projecting rim-band. The inner wall of said rim-band preferably aligns with the adjoining outer wall portion thereabove, as is clearly shown in Fig. 1. Thus in molding the body portion 21, the mold may have a core pin (not shown) extending up into the open side 20a and terminating in a form to produce the opening 21j, yet leaving the rim 21a continuous and unbroken.

As was described above, the width of sockets 21d are enlarged at the inner end walls 21g to provide the shoulders 21h. This construction can be readily provided during the molding operation of the body portion 21 by a so-called "stripping" step, that is, by using core portions of the mold (not shown) which form sockets 21d having enlarged ends corresponding to the contour forming the shoulder 21h and by removing such core from the molded body portion 21 while it is still hot and in an expanded condition. The enlarged ends of such core may be slipped out, that is, "stripped out" so that when the hot molded body portion 21 cools and hardens, the under cut anchoring pockets with shoulders 21h are produced as shown in Fig. 3.

From the above description and the drawings, the invention will now be apparent. After constructing the molded body portion 21, terminal blades 22 and spring contacts 23, as shown in Figs. 1 to 3, 6 and 7, the assembly operation of the fitting is quite simple to accomplish. First, the spring contacts 23 are inserted in the passages 21b of the body portions 21 where they are retained against displacement during assembly operation by the clamping of the ledges 21e between flanges 23e and spring contact side 23c. Next the end bases 22a of the blades 22 are inserted in the sockets 21d. Since the width of these end bases 22a are made substantially the width of the sockets 21d and as there may be only a slight give to the tongues 22d, very little pressure and force is necessary to start the entry of end bases 22a into the sockets 21d. When the tongues 22d reach the level of the wedges 21f, the latter enters the splits in the end bases 22a and cam the tongues 22d laterally into the pockets and under the shoulders 21g making an irremovable firm anchorage without scoring or otherwise scratching the walls of the sockets other than tightly squeezing or perhaps biting the spurs 22f into the pocket walls to form a rigid attachment.

It should be noted that the splits provided in end bases 22a to form the tongues 22d are of substantial width which are carried up to the offset portions 22c, and the cut-out portion 22e forming the spurs 22f further reduce the cross-sectional area of the tongues 22d to increase the effective resilience thereof as is clear from Figs. 3 and 6.

Simultaneously with the insertion of the end bases 22a into the sockets 21d as above described, the bowed flange 23e contacts the flat side surfaces of the tongues 22d causing the bosses 23g to make an efficient scraping electrical contact therewith on inserting the end bases 22a in final anchored position. As shown in Figs. 1 and 3, the width of each socket 21d is made to just accommodate the thickness of the tongue 22d and the flange 23e, the latter being flattened from its initial bowed condition during the inserting operation.

The current carrying contact members having been securely anchored in the body portion 21, it completes the fitting 20 which now may have connected therewith the conductor wires 24 which have the ends thereof passed through opening 21j. It will be noted that in fitting 20, the bared ends of wires 24 may be soldered to the current carrying member as at 25 on the blade offset portion 22c, such soldered joints being found more practical, efficient and reliable than clamped or screw binding post terminals for apparatus having radio circuits, Christmas lighting units and other portable appliances.

75 Where it is desirable to provide screw binding

post terminals instead of solder joints 25, blades 122 may be provided which are similar in construction to blades 22 shown in Fig. 6 with the exception that offset portion 122c of blades 122 are provided with ears or extensions 122j which carry binding post screws 122k for electrically connecting the conductor wires 24 thereto as shown in Fig. 8.

In Figs. 1 and 10 the novel combination of blades and body portions are shown in combination for providing the plug caps 30. Here conductor wires 34 pass into the body portion 31 preferably through the rounded closed front side 30b opposite the rear open side 30a and connect with the blade members 22 which are permanently anchored in socket 31d in the identical manner described above for fitting 22 and as shown in Fig. 1.

Since cap-plugs 30 are not intended to provide an extra current-tapping means incorporated therein, which the spring in contacts 23 in passages 21b, etc. form in fitting 21, such spring contact and passage constructions, etc. are omitted and the conductor wires 34 may be soldered to base offset portions 22c at 35.

Where binding post terminals are required, the solder joint 35 may be replaced by screw binding posts 132k threaded directly into the offset portion 22c as shown in Fig. 9, such construction permitting body portions 31 of fittings 30 to be made smaller than would be otherwise possible.

It will thus be seen that there is provided means whereby the several objects of this invention are achieved and which are well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. An electrical fitting of the character described comprising a rigidly molded body and terminal contact blade members mounted to extend therefrom, said body having an opening extending in from one side thereof and parallelly aligned sockets spaced from said opening extending in from another side of said body, said sockets having under cut pockets at their inner ends, a conductor wire passing through said opening and electrically connecting with the blade members, said blade contact members having expandable bases each being decreased in cross-sectional area at a mid-portion to enlarge an end thereon fitted into said sockets, camming means forming part of the walls of said sockets for engaging and expanding said base ends so constructed and arranged that said expanded contact end portions grip the ends of said bases beyond the mid-portions thereof occupying said pockets for irremovably anchoring the blade members in rigid mounted positions.

2. In an electric fitting of the character described, a spring contact current carrying member formed of a strip of material bent into a right triangular shape structure with one side thereof disconnected from the adjacent side at a corner, and a flange formed from an edge portion of one of said sides at the corner, said flange

and the disconnected adjacent side forming a clamp retaining means for resiliently engaging therebetween a body portion of the fitting while two adjacent sides of the structure may be flexed with respect to the remaining side.

3. In an electric fitting of the character described, a spring contact current member defined in claim 2 in which said flange is bowed outwardly to increase its resiliency.

4. In a cap-plug construction of the character described having a terminal blade formed with a base, a spring contact of a current carrying member of triangular shape having one corner portion thereof detached to permit the adjoining and the opposite side of said member to be flexed with respect to the other side, said last mentioned side having a flange extending in the direction of said adjoining side for contacting the exterior surface thereof with said terminal blade base, said flange and adjoining side resiliently engaging therebetween a body portion of the cap-plug.

5. In the cap-plug construction of the character described, a spring contact defined in claim 4 in which said flange is bowed and provided with scraping means for increasing said contacting effect between the flange and the blade base.

6. In an electric fitting construction of the character described, a rigidly molded insulating body formed with spaced passages extending therethrough and sockets extending in from one side of the body part way therethrough alongside the passages, ledges provided in the common wall between said passages and sockets, spring contact current carrying members fitted in said passage, said members having clamping means engaging the ledges, current carrying terminal contact blades having expandable base ends anchored in said sockets, cam means projecting from parts of the wall of said sockets for expanding the base ends on inserting the latter fully in the sockets for making the anchorage of the blade members in the sockets irremovable, parts of said clamping means being so constructed and arranged to contact with the blade base ends in the sockets.

7. In an electric fitting construction of the character described, a rigidly molded insulating body formed with recessed portions or sockets extending in from a side thereof and passages extending alongside said sockets through said body, current carrying terminal contact blades having expandable base ends anchored in said sockets, cam means projecting from parts of said socket walls for expanding said base ends on inserting the latter fully in the sockets for making the anchorage of the blade members in the sockets irremovable, spring contact current carrying members of triangular shape fitted in said passages, said spring contact members having one corner of each detached to permit the adjoining and the opposite sides of each member to be flexed with respect to the remaining side, said remaining sides having flanges facing the passages for contacting the exterior surface of the flanges with blade base ends in said sockets.

8. In the electric fitting construction defined in claim 7, the flange being bowed outwardly to provide spring pressure of the contact of said flange surface with the blade base ends.

JOHN PETRY.
